WATERPROOF GARMENT

Valerie Margaret Frances Gordon,
Camberley, EnglandApplication November 21, 1949, Serial No. 128,530
In Great Britain January 4, 1949

6 Claims. (Cl. 128—287)

1

This invention relates to waterproof knickers or like garments for example for babies, the main object being to provide a knicker-like garment which can be quickly and easily applied, will be comfortable to wear, and may be used with cotton wool or other absorbent material which is thrown away when soiled, and thereby avoids the use of the usual babies' napkins and the considerable amount of work involved in washing and drying them. It has been found that the use of waterproof knickers over the usual napkins keeps the baby too hot and tends to make the baby's skin tender and sore. I have found that special construction is desirable to avoid this overheating and to ensure a comfortable enfolding of the buttocks.

According to the present invention I provide a garment having separable ends to form the waist wherein the back edge is between 60 and 85 per cent wider than the front edge, and the sides are cut away to leave the front edge wider than the narrowest part of the garment which narrowest part is located between transverse lines one-sixth and one-half of the length of the garment from the front edge, said narrowest part being from 5 to 40% smaller than the front edge. The side edges may be curved in concave manner from the narrow end to the narrowest part and are straight or convex from the wider end to the half-way line across the garment. The back edge may be curved so that the middle point of the back edge is higher than the remainder of that edge. Also according to the invention I provide a garment having separable ends to form the waist, means to adjust the size of the waist by holding the back in any required gathered condition, and means to adjust the size of the leg holes by holding the back of the leg holes in any required gathered condition; all the gathering being at the back of the body, causing fullness in the correct place to fit the rounded buttocks. The means for holding the side edges gathered may be effective over lengths located within position 25% of the length of the garment from each end thereof measured along the centre line. The means for holding the gathers at each position may comprise a pair of tapes, one or two hems, which tapes emerge from adjacent eyelet holes over which the ends of the tapes can be tied. These and other features of the invention will now be described by way of example with reference to the accompanying diagrammatic drawings, wherein:

Figure 1 is a view of one side of a garment (in flat condition) made in accordance with the invention;

2

Figure 2 is a view of the other side of the garment; and

Figure 3 is a view of the garment in the fitted condition.

The garment consists of a sheet 10 of plastic material having a wide end or edge 11 and a narrow end or edge 12, these ends being separable but adapted to be attached together at or near their corners so as to encircle the waist. The wide end 11 is placed at the back and the narrow end 12 is placed in front. The back edge is between 60 and 85 per cent wider than the front edge and of such length as to bring its corners around the sides of the baby's waist. The side edges 13, 14, are cut away so that the end 12 is wider than the narrowest part of the garment which extends from 16 to 17 which is located between transverse lines 18, 19 which are one-sixth and one-half respectively of the length of the garment from the front edge 12. The sides 13, 14 are curved from the end 12 to the narrowest part 17 to form a concave shape. From the end 11 however the sides 13, 14 are straight or convex down to about the halfway line 19. The back edge 11 is curved in the direction to make the middle point of the back edge higher than the remainder of that edge. The wide end 11 is between 80 and 110 per cent of the length of the garment.

This shape forms a large part between 16 and 11 which comfortably surrounds the buttocks and narrow part 16 to 17 which not only engages between the legs but also engages along the groin without chafing and providing extending corners at both ends which can be connected at the front of the sides so as to engage around the thighs without completely wrapping in the thighs whereby the movements of the baby induce air currents into the garment which keeps him cool.

The corners are connected together preferably by press-stud fasteners but buttons, bows, buckles, and similar connectors can also be used.

As shown in Figure 1 press stud sockets 21, 22, 23, 24 are provided at or closely adjacent to the edge 11. The sockets 22, 23, are spaced apart a distance less than the length of the garment. The sockets are provided only at the back edge and do not extend down the leg which would unduly enclose the legs and buttocks and would keep the baby too hot. Press stud spigots 26, 27, 28, 29, are provided at or near the narrow end 12 and face in the opposite direction to the direction in which the sockets face in the open condition of the garment so that the back corners can overlap the front corners and the spigots 26, 27, 28, 29, fit into sockets 23, 24, 21, 22, re-

spectively. The spigots 26, 29, are arranged nearer to the edge 12 than the spigots 27, 28, so that the overlapped top edge of the end 11 is at an angle to the front top straight edge 12. This helps to shape the garment to the groin and keeps the front edge from sagging. This overlap (i. e. from 21 to 22 and 23 to 24) may be about three-quarters of an inch to two and a half inches.

The garment may be reinforced to carry the press stud elements e. g. by strips of canvas, linen, plastic, "nylon," or the like, as shown for example at 30 in Figure 1.

As can be seen from Fig. 3, the garment is hung from the waist (the rims 11 and 12), so that the size of leghole can vary with the movement of the baby allowing freedom of entry of air. The overlap 21 and 32 allows a telescopic effect and gives as complete enfolding of the baby as is necessary.

The large end at 35 comes well round the back of the thighs but the recessed sides 36 fit the groin.

In order to further shape the garment and at the same time to make it adjustable to the size of the baby, it is provided with means to hold the back of the waist in gathered condition, and means to hold the edges of the garment in gathered condition at the backs of the leg holes but not at the front edges of the leg holes. Thus at the back edge 11 (Figure 1) two plastic tapes or cords 37 and 38, are provided between the fasteners 22, 23. These tapes are located in a hem which may be formed by turning over the edge of the garment and stitching it as at 40. The tape 37 passes through an eyelet hole 41 and through the hem in one direction viz., towards the socket 22 where its end is secured by stitching or otherwise. The tape 38 passes through an eyelet 42 and right along the hem in the opposite direction to the tape 37 and is secured at the socket 23. The eyelets are located closely adjacent to each other and by pulling up the tape 38 the edge 11 can be gathered snugly around the back. The ends of the tapes 37, 38 can then be tied together or the end of the tape 38 may be knotted. Similarly at the sides two tapes 44, 45, pass through eyelets 46, 47, and two tapes 49, 50, pass through eyelets 51, 52. The inner ends of the tapes 45, 50, are secured at about the positions 16 so that the gathered length 16 to 50 is only at the backs of the thighs. This provides the desired rounded shape of the large end of the garment. The front of the garment is not gathered. This helps to hold the pad in place, gives a neat appearance and avoids irritation which would be caused by gathering against the tender inside of the groin. The positions where gathering can start may be arranged at about 25% of the length of the garment from each end thereof i. e. as a maximum from line 52 to line 52. The effective length to be gathered at the side edges may be 30 to 35 per cent of the length of the garment measured along the centre line and is nearer to the end 11 than the end 12.

If desired the two tapes may pass side by side through the hem to emerge at adjacent eyelet holes. The eyelets 41, 42, as shown are near one end of the back edge, and the eyelets 46, 47, 51, 52, are at the upper ends of the parts to be gathered, these positions being particularly convenient to be reached when the baby is lying on his back. Instead of anchoring the tapes at one end, both ends may pass out of eyelet holes.

The length to be capable of gathering at each

side may for a baby's garment be three to seven inches in length when stretched and located opposite to a length on the longitudinal centre line between a point six inches from the narrow end and three inches from the curved end.

In the open condition the tape in a baby's garment measuring along the centre line from the anchored end to the eyelet, may be within a length two and a half inches from the large curved end and four and a half inches from the small straight end. The straight end in the front is not drawn together and this keeps the front in a more or less flat shape in side view.

The garment may be made double thickness 15 as it is found that a double thickness of thin material guards against tearing whilst being softer than a single thickness of thicker material and tends to prevent plasticised compositions from becoming hard and brittle. The double thickness 20 can have two spaced lines of stitching near each short end to serve in place of a double hem. "Nylon" thread would be very suitable for stitching.

Conveniently a baby garment may be 13-16 25 inches e. g. 14½ inches across the straight short end, and the same across the corners at the other short end, 16 to 18 inches, e. g. 17 inches along the longitudinal median line, and 6 to 8 inches e. g. 7 inches across the middle. The curved short end may have a curvature about the centre point of the garment. In one desirable construction the straight end is made from 6 to 10½ inches wide while the curved end is 11 to 17 inches wide so that its corners come 30 to the front of the baby near its sides. The wide end may be from 60 to 85 per cent greater than the width at the narrow end. The length of the garment when flat may be approximately the same as the width of the large end. The garment may be waisted down to 4 to 7½ inches i. e. smaller than the width of the narrow end, at a position about three quarters of the way from the wide end towards the narrow viz., the narrowest part of the garment is near the narrow end.

45 The sheet material may be plasticised vinyl plastic e. g. a plasticised vinyl chloride or co-polymer of vinyl chloride and vinyl acetate. Alternatively the material may be rubber or rubberised textile, or polyvinyl plastic coated textile, or nylon. The garment may be made partly of plastic and partly of nylon or other woven material.

50 The garment may be larger if intended for older children or adults.

The invention enables a construction to be provided which by reason of shape and overlapping around the thighs enables air to enter at the thighs and circulate to prevent overheating 60 of the baby but nevertheless provides a waterproof fitting thereby having the advantages of rubber knickers without the disadvantages. The shape of the garment also holds the absorbent padding in place without requiring pockets or other means for holding it. The invention also 65 obviates the need for safety pins with their well known disadvantages such as the mother worrying whether the baby has swallowed a pin if the pin is missing or whether the pin is sticking in the baby if the baby is crying. The use of non-adjustable elastic is also avoided with its attendant disadvantages of being sometimes too tight or, when the rubber ages, too loose, and not being adjustable. A further advantage of 70 the invention is that the use of absorbent pads 75

with the waterproof garment minimises the contact area of the baby's skin with wet material. The garment of the present invention is more quickly applied than an ordinary napkin.

The special method of adjusting waist and leg holes, ascertains that there need be no leakage whatever the size of baby.

I claim:

1. A waterproof knickers-like garment comprising a sheet of waterproof material having connectible ends to form the waist wherein the back edge is between 50 and 85 per cent wider than the front edge, and is between 80 and 110 per cent of the length of the garment, and the sides are cut away to leave the front edge wider than the narrowest part of the garment which narrowest part is located between transverse lines one sixth and one half of the length of the garment from the front edge, said narrowest part being from 5 to 40% smaller than the front edge, connecting means for connecting the corners and which means are located only adjacent the back edge and adjacent the front edge, said connecting means comprising fastener means at each corner spaced apart around the waist in such positions that the corners of the back edge considerably overlap the corners of the front edge and can be fixed in the overlap position, draw tape waist adjusting means to adjust the size of the waist by holding the back in any required gathered condition, and draw tape side adjusting means provided in the backs only of the legholes to adjust the size of the legholes by holding the backs of the legholes in any required gather condition; all the gathering being at the back of the body, causing fullness in the correct place to fit the rounded buttocks, the remaining side edges under the crutch and in the groin being free from draw tapes.

2. A waterproof knickers-like garment comprising a sheet of waterproof material having connectible ends to form the waist wherein the back edge is between 50 and 85 per cent wider than the front edge, and is between 80 and 110 per cent of the length of the garment, and the sides are cut away to leave the front edge wider than the narrowest part of the garment which narrowest part is located between transverse lines one sixth and one half of the length of the garment from the front edge, said narrowest part being from 5 to 40% smaller than the front edge, the side edges being progressively narrower from the wide end to the halfway line across the garment, the back edge being curved in the ungathered condition so that the middle point of the back edge is higher than the remainder of that edge, connecting means for connecting the corners and which means are located only adjacent the back edge and adjacent the front edge, said connecting means comprising fastener means at each corner spaced apart around the waist in such positions that the corners of the back edge considerably overlap the corners of the front edge from three quarters

of an inch to two and a half inches and can be fixed in the overlap position, the fasteners at the narrow end at each corner being arranged with the outer one nearer to the top front edge than the other so that the overlapped top edge of the wide end is at an angle to the front top straight edge, draw tape waist adjusting means to adjust the size of the waist by holding the back in any required gathered condition, and draw tape side adjusting means provided in the backs only of the legholes to adjust the size of the leg holes in any required gathered condition; all the gathering being at the back of the body, causing fullness in the correct place to fit the rounded buttocks, the remaining side edges under the crutch and in the groin being free from draw tapes, said side adjusting means being effective over lengths located within positions 25% of the length of the garment from each end thereof measured along the centre line, the effective length to be gathered at the side edges being 30 to 35 per cent of the length of the garment measured along the centre line, each of said waist and side adjusting means consisting of a piece of tape contained in a hem, at least one end of the tape passing out of the hem through a hole leaving a free end which can be fixed after adjusting the amount of gathering.

3. A garment as claimed in claim 1 wherein the fasteners consist of a pair of press stud elements at each corner arranged so that in the flat condition of the garment the projecting spigots at one corner face in the opposite direction to the direction in which the corresponding recesses face.

4. A garment as claimed in claim 1 wherein at least one edge to be gathered as a hem and two tapes passing through the hem and emerging from two adjacent eyelet holes where the tapes can be fastened at the required adjustment.

5. A garment as claimed in claim 1 wherein the two tapes are disposed in parts of the hem on either side of the eyelet holes.

6. A garment as claimed in claim 1 wherein a pair of such eyelet holes are placed near one end of the back edge, and a pair of such eyelet holes are provided at the upper ends of the parts of the edges of the leg holes to be gathered.
